UNITED STATES PATENT OFFICE.

MARTIN O. ELVESTROM, OF BRICELYN, MINNESOTA.

SCAFFOLDING.

1,101,839.

Specification of Letters Patent. Patented June 30, 1914.

Application filed April 26, 1913. Serial No. 763,721.

To all whom it may concern:

Be it known that I, MARTIN O. ELVESTROM, a citizen of the United States, residing at Bricelyn, in the county of Faribault and State of Minnesota, have invented certain new and useful Improvements in Scaffolding; and I do hereby declare the following to be a full, clear, and exact description of the invention, such as will enable others skilled in the art to which it appertains, to make and use the same.

My invention relates to improvements in scaffolding adapted for general use, but is especially designed for use on silos and like buildings.

To the above ends, generally stated, the invention consists of the novel devices and combinations of devices hereinafter described and defined in the claims.

In the accompanying drawings, which illustrate the invention, like characters indicate like parts throughout the several views.

Referring to the drawings: Figure 1 is a diagrammatic section, taken vertically through the upper portion of a silo and having mounted thereon my improved scaffolding, shown in side elevation; Fig. 2 is a plan view of the improved scaffolding, with some parts removed and some parts broken away; Fig. 3 is a detail view in section, taken on the line x^3-x^3 of Fig. 2, on an enlarged scale; Fig. 4 is a detail view principally in section, taken on the line x^4-x^4 of Fig. 1, on an enlarged scale; Fig. 5 is a side elevation of the parts shown in Fig. 4, with some parts removed; Fig. 6 is a view partly in side elevation and partly in section, taken on the line x^6-x^6 of Fig. 2, on an enlarged scale, some parts being shown in different adjustments, by means of dotted lines; Fig. 7 is a detail view partly in side elevation and partly in section, taken on the line x^7-x^7 of Fig. 6; and Fig. 8 is a transverse section, taken on the line x^8-x^8 of Fig. 7, on an enlarged scale.

For the purpose of illustrating my improved scaffolding in working position, a portion of a silo has been shown in the drawings.

The numeral 1 indicates the walls of the silo and the numeral 2 the conical roof thereof. Anchored at the apex of the roof 2 is a stub post 3.

The numeral 4 indicates the A-frame of the scaffolding anchored to the post 3, for vertical adjustment and for circumferen-

tial movement around the post 3, by an anchor bar 5 and a collar 6. One end of the bar 5 is pivotally secured, by a bolt 7, to a pair of laterally spaced anchor lugs 8, integrally formed with the collar 6, and the other end of said bar 5 is adjustably secured to the apex of the frame 4 by nut-equipped bolts 9, passed through alined perforations in said bar 5 and the two side bars of the frame 4. As shown, the side bars of the frame 4 are preferably constructed from angle irons. The collar 6 is made in two sections connected by nut-equipped bolts 10, to permit the same, when separated, to be applied around the post 3. This construction will be found very convenient in applying the collar 6 to a tall pole, such as a flag staff, as it would not be necessary to slip the collar over the top of the pole, as is now customary. To insure free and easy rotary movement of the collar 6, the same is mounted in a two-part bushing 11, applied around the post 3.

A pair of supporting wheels 12, set one ahead of the other, to run on the roof 2, are mounted one on each of the side bars of the frame 4. Mounted in the hub of each wheel 12 is a bushing 13, having flanged ends that embrace the adjacent faces of the wheel hubs. One of the flanges of each bushing 13 is made removable, to permit the bushings to be telescoped into the wheel hubs. For locking the wheels 12 against lateral movements on the side bars of the frame 4, a pair of vertically spaced tapered pins 14 are driven into perforations formed in the horizontal flanges of the side bars of the frame 4. These pins 14 also keep the parts of the bushings 13 assembled in the wheel hubs.

A horizontally extended shaft 15 projects transversely across the free end portion of the frame 4 and is journaled, at its ends, in upwardly extended bearings 16, secured to the side bars of the frame 4. Set screw equipped collars 17 hold the shaft 15 against endwise movement in its bearing 16. Keyed or otherwise secured to the intermediate portion of the shaft 15 is a windlass drum 18.

Extended transversely under the shaft 15 is a counter shaft 19, journaled in sleeve-like bearings 20, and held against endwise movements therein by set screw equipped collars 21. The bearings 20 are secured to stirrups 22, for different adjustments, by cross heads 23. The stirrups 22 are rigidly

secured to the cross tie bars 4^a of the frame 4, and they are preferably constructed, as shown, from T-irons having their intermediate flanges turned inward. Outwardly projecting trunnions 24 on the bearings 20 are journaled in bearing lugs 25 on the cross heads 23, to permit vertical swinging movement of the bearings 20. Nut equipped bolts 26 are provided for frictionally clamping the cross heads 23 onto the intermediate flanges of the stirrups 22. Keyed or otherwise secured to the intermediate portions of the counter shaft 19 is a worm 27, which meshes with a gear 28, rigidly secured to the shaft 15. On the outer projecting end of the counter shaft 19 is a grooved sheave 29, having mounted thereon a depending operating cable 30. A platform or workman's seat 31 is suspended from the windlass drum 18 by cables 32, arranged to be wound onto or unwound from the windlass drum 18. The cable 30 is of a length sufficient to extend within reach, at all times, of the platform 31.

Obviously, by operating the cable 30, the windlass drum 18 may be rotated in either direction, at will, through the several connections extending from the sheave 29 to the shaft 15. The cable 30 will pinch or bind in the groove of the sheave 29 and prevent slipping of the same thereon. It may easily be seen that, by adjusting the cross heads 23 on the stirrups 22, the counter shaft 19 can always be kept in a horizontal position, irrespective of the pitch of the roof to which the scaffolding is applied. By the use of my improved scaffolding, one can work completely around the silo and at any elevation thereof, without changing the scaffolding after the same has once been secured in position. By adjustably connecting the A-frame 4 to the bar 5, the platform 31 can be set at a convenient working distance from the walls of the silo, irrespective of the diameter thereof. Obviously, the worm 27 and gear 28 will lock the windlass drum 18 against rotation and thereby support the platform 31 where set.

What I claim is:

1. In a workman's scaffolding for silos and the like, a frame having means for pivotally anchoring the same to a roof, provided, near its free end, with wheels located one ahead of the other and arranged to run on said roof, a windlass and a worm and gear, for operating the same, mounted on the free end of said frame, a platform having a cable suspended from said windlass, means for rotating said worm in either direction, at will, from said platform, including a sheave connected to said worm, a cable working on said sheave, and means for changing the angularity of said sheave with respect to said platform.

2. In a workman's scaffolding for silos and the like, a frame having means for pivotally anchoring the same to the roof and provided, near its free end, with wheels located one ahead of the other, and arranged to run on said roof, a windlass shaft journaled on the free end of said frame, a shaft journaled on said frame, for angular adjustments with respect thereto, a worm and gear connection between said two shafts, a platform having a cable suspended from said windlass shaft and means for rotating said worm shaft in either direction, at will, from said platform.

3. In a workman's scaffolding for silos and the like, the combination with a roof having an anchoring post, of a longitudinally divided sleeve loosely journaled on said post, a frame, a bar pivotally secured to said sleeve for vertical movement and adjustably connecting the apex of said frame to said sleeve, wheels set one ahead of the other, and journaled on said frame, to run on the roof, and a platform suspended from the free end of said frame.

In testimony whereof I affix my signature in presence of two witnesses.

MARTIN O. ELVESTROM.
